WIRE COATING APPARATUS

Randall W. Schultz, Bloomsburg, Pa., assignor to
Metalloys Company, Williamsport, Pa., a cor-
poration of Pennsylvania

Application May 15, 1940, Serial No. 335,414

3 Claims. (Cl. 22—57.2)

The invention is an improvement on the apparatus for coating wire or other metal articles shown, described and claimed in my United States Patent No. 2,072,060, granted February 23, 1937. More particularly, it is an improved die casting structure for that apparatus. The construction shown and claimed herein is a simplified and more efficient arrangement for casting the coating on the foundation wire or other article.

In view of the fact that this invention is a specific improvement on the apparatus of my said Patent No. 2,072,060, it will not be necessary to illustrate the whole apparatus herein, and only sufficient parts of the old structure will be shown and described as are necessary to understand the improvement.

In general, this invention is in the casting die and the cooperating elements. This part of the original machine is shown in Figs. 6 to 11 of my earlier patent referred to.

In the drawing of the present application:

Fig. 1 is a sectional view of the casting elements and cooperating devices.

Fig. 2 is an enlarged view of the leading guide by means of which the article to be coated is properly centered in the apparatus.

Fig. 3 is an enlarged view of the die and the means for holding the same in position.

Fig. 4 is a plan view of the main guide by means of which the wire or other article is directed through the casting die.

As far as practicable, the same reference characters used in the patent will be used in this application.

Referring to the drawing, 30 represents the manifold or other source of supply through which the coating metal flows in a channel 31 to a chamber or well 100. This well which receives the coating metal from the manifold 30 has associated with it a supplemental or auxiliary well 101. The opening between the chamber 100 and the auxiliary or supplemental well 101 is controlled by a valve 102.

The casting die 44, Fig. 3, is substantially like the casting die so numbered in my said earlier Patent No. 2,072,060; and associated therewith is a guide 59 which corresponds to one of the two guides used in my prior patent. The casting die 44 is provided with a central opening 45 of the size of the wire or other article after the coating metal has been applied. The guide is provided with a central opening 60 of the size of the wire before the same is coated. It is essential that the opening 60 of the guide shall be

concentric with the opening 45 of the die, for the difference between the size of the hole in the guide and the size of the hole in the die determines the thickness of the coating metal. The position of the die and its guide, and the means for holding the openings in these two members concentric, may be varied at will; it is only essential that the position of these two parts with respect to each other shall be exactly maintained. As here shown, the die 44 and the guide 59 are held in position in the auxiliary chamber 101 by means of a plug 103 which screws into an internally threaded recess 104 directly beneath the auxiliary or casting chamber 101. This plug 103 itself has a recess 105 within which the casting die 44 closely fits. The guide 59 is provided with a ledge 107, which rests on the die 44 and engages around lip 106 thereon and holds the die and guide in position and in proper spaced relation one to the other. As the plug 103 is screwed into position, the casting die 44 and the guide 59 are held in place against the bottom of the auxiliary well or chamber 101. While this is a simple means for holding the casting die and its guide in position with respect to each other and with respect to other parts of the apparatus, it is to be understood of course that any other suitable positioning arrangement may be used.

The guide 59 is provided with a series of openings 61 arranged around the central opening 60 so that the fluid metal can flow from the auxiliary well through these holes in the guide and on through the casting die as the wire to be coated passes therethrough.

The valve 102 which controls the opening between the chamber 100 and the auxiliary chamber 101 is arranged on the end of a somewhat elongated stem 110 which extends up through the cover 111 of the chamber 100 and through the stuffing box 112 and packing gland 113. This valve stem 110 is threaded at 114 where it passes through the gland 113 and has fixed to the upper end thereof a handle 115 by which it may be turned in the gland 113 to open or close the valve 102. The valve stem 110 has an opening throughout its length through which the wire or other article to be coated may pass.

The opening or passageway through the valve stem is provided at the top thereof with a plug 57, Fig. 2. This may be secured in place in any convenient way. As here shown, the plug is threaded, and is screwed into cooperating threads arranged within the passageway through the valve stem 110. This plug 57 has an orifice 58

running from top to bottom therethrough, which orifice preferably is somewhat enlarged at its upper end, as at 58'. The functions of plug 57 and orifice 58 will be explained fully below.

- 5 As here shown, the material to be coated 10 passes around a wheel or drum 85 as it comes from the preliminary coating bath, as in my earlier patent referred to. This wheel or pulley is mounted for rotation on an axis supported by 10 one or more columns 86 secured to the top of the casting 87 through which passes the channel 30. It may of course be supported in any other suitable manner, but the periphery of the pulley must be so positioned that the wire or other material to be coated shall align substantially with the hole 58 in the plug 57; so that the wire shall pass down over this pulley 85, through orifice 58, through the valve stem, through the guide 59 and the casting die 44.
- 15 20 In the bottom of the casting constituting the principal and auxiliary chambers 100 and 101 is an electric heater 75 held in position by an extension 77 forming a part of the closure 78. Any other means for enclosing the electric heater 25 would be the equivalent of this construction.

As in my said Patent No. 2,072,060, the invention contemplates the application of the coating by suction beneath the die rather than by a positive pressure from above. As stated in the patent 30 referred to, the use of a construction which produces a vacuum or a partial vacuum in the die chamber has certain distinct advantages over an apparatus which operates by building up pressure above the die; for it has been found that if 35 oxygen is present in substantial amounts in the die chamber, considerable oxidation of the parts and of the coating metal takes place at the high temperatures used, and this oxide tends quickly to clog the orifice in the die. When the air is exhausted from beneath the die, this objectionable 40 oxidation does not take place. While any preferred means for producing the suction may be used, I have here shown an ejector of substantially the same type as that disclosed and de- 45 scribed in detail in my said Patent No. 2,072,060. Since no novelty is claimed in this ejector, it will not be described here. It is shown in the drawing as having a head 90 which is screwed or otherwise secured in the member 94.

50 Generally, the operation of this improved apparatus is similar to that of the structure shown and claimed in my Patent No. 2,072,060; but there are several important differences, and so the operation will be described in detail.

55 The valve 102 is normally closed when the apparatus is at rest. Assuming now that the wire or other article to be coated 10 has been run over the wheel 85, threaded through orifice 58 in plug 57, through the longitudinal opening in valve 60 stem 110, through opening 60 in guide 59, and through the casting die 44, and is secured to a spool or other device for drawing the wire through the apparatus, and assuming that a supply of molten metal is available and has been run into 65 chamber 100, the coating operation is begun by opening the valve 102 and by causing the wire or other article to be moved downwardly through the machine.

70 As soon as the valve 102 is moved from its seat, the molten metal will run up into the opening through valve stem 110, until it reaches a level substantially that of the metal in the melting pot. The exact height reached by the metal in the valve stem will depend upon several factors, as, 75 for instance, the head of metal, the size of the

opening in the stem, the size of the article to be coated, and the rate of motion of the latter.

Preferably, the diameter of the passageway through the valve stem 110 is (as shown in the drawing) considerably greater than the size of 5 the article to be coated. This is for the reason that the moving wire will, of course, entrain some of the molten metal, and if the wire should substantially fill the passageway, the molten metal would not fill the stem. 10

The orifice 58 in plug 57 is smaller than the opening through the valve stem; in fact, it is made preferably just large enough to permit free running of the article to be coated. This feature is not important except where the head of metal 15 is higher than the top of the valve stem. Under such conditions, the metal would, of course, run out at this point. By making orifice 58 relatively small, this difficulty is avoided, for the moving wire will entrain enough of the metal to prevent 20 an overflow.

As stated in my said Patent No. 2,072,060, it is desirable that the wire to be coated shall pass through the coating metal for as great a distance 25 as may reasonably be possible. This long immersion provides two chief advantages: first, the wire is raised to the proper temperature; and, second, the coating metal is alloyed with the surface of the wire, and thus furnishes an ideal base 30 for what is really the final coating. By arranging that this immersion takes place principally before the wire passes through opening 60 in guide 59, and that the distance between guide 59 and casting die 44 is relatively short, it has been 35 found that whereas the coating will alloy thoroughly with the wire above guide 59, the final coating, applied at die 44, has very little time in which to alloy with the surface of the wire, and so the final coating is virtually pure metal.

The novel valve stem of the present invention 40 provides an immersion of the wire in the molten metal of considerably greater duration than has heretofore been conveniently possible. In fact, it will be seen that, without enlarging or changing the principal elements of the machine, the 45 length of the immersion may be varied at will by merely varying the length of the valve stem and the head of the metal.

There are further important advantages of 50 the present structure. From the time the wire enters the valve stem through opening 58 until it emerges at the bottom thereof, it passes through a body of metal which is substantially at rest, except for the motion produced by the wire itself, and this motion is in the same direction as the movement of the wire. Below the valve, also, in the well 101, the wire exerts a force 55 on the molten metal, and aids the flow into the die.

There are no substantial turns or angles to 60 interfere with the flow of metal. And there is less relative movement between the wire and the metal than before; in this apparatus, most of the movement is concurrent.

The speed of movement of the wire to be 65 coated can be adjusted to suit the requirements of the coating metal, the stock to be coated, etc. As the wire passes through the ejector, it, with its newly applied coating, is cooled by the fluid flowing through the ejector, and is then wound 70 up, or disposed of in any other desired manner, as it emerges from the bottom of the apparatus.

I claim:

1. In a wire coating machine, the combination 75

of a die chamber, a casting die therein, a guide in cooperative alinement with the casting die, a well to receive and hold the coating metal adjoining the die chamber, a valve seat between the well and the die chamber, a valve adapted to cooperate with the seat, a stem for the valve, the valve and its stem having a passageway therethrough for the material to be coated, and means for moving the valve away from and toward the valve seat.

5 2. In a wire coating apparatus, the combination of a casting die chamber, a casting die arranged therein, a guide having a guiding orifice therein and arranged with its orifice in line with and concentric to the opening in the casting die, a well to receive and hold the coating metal located adjacent the die chamber and communicating with the die chamber through a valve controlled opening, a valve and valve stem there-
10 for having a passageway therethrough for the passage of the material to be coated, and means

to vary the position of the valve so as to control the flow of coating metal from the well to the casting chamber, substantially as described.

3. In a wire coating machine, the combination of a die chamber, a casting die therein, a guide 5 adjacent the die having a guiding orifice in alinement with the orifice in the casting die, a well for receiving the coating metal arranged adjacent to the die chamber and communicating therewith through a valve controlled opening, 10 a valve and valve stem therefor having a passageway for the passage of the material to be coated, the valve being adapted to control the opening between the well and the die chamber, the orifice through the valve stem being in sub- 15 stantial alinement with the orifices in the guide and casting die, means for opening and closing the valve, and a stuffing box in the top of the well through which the valve stem passes.

20

RANDALL W. SCHULTZ.
